UNITED STATES PATENT OFFICE.

EDWARD RAWSON, OF MOSCOW, IDAHO.

PLANER.

SPECIFICATION forming part of Letters Patent No. 715,145, dated December 2, 1902.

Application filed February 12, 1902. Serial No. 93,684. (No model.)

To all whom it may concern:

Be it known that I, EDWARD RAWSON, a citizen of the United States, and a resident of the city of Moscow, in the county of Latah and State of Idaho, have invented a new and Improved Planer, of which the following is a full, clear, and exact description.

The invention relates to woodworking machinery; and its object is to provide a new and improved planer which is simple and durable in construction, very effective in operation, and more especially designed for reducing timber to any desired thickness and width and arranged to permit the operator to shift the side cutter-heads independent one of the other while the machine is running.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all of the views.

Figure 1 is a longitudinal sectional elevation of the improvement. Fig. 2 is a plan view of the same with part broken out. Fig. 3 is a front end elevation of the same. Fig. 4 is a transverse section of the same on the line 4-4 of Fig. 1. Fig. 5 is a side elevation of a ratchet device for the carriage-shifting device; and Fig. 6 is an end view of the same, parts being broken out.

The improved planer is mounted on a suitably-constructed frame A, supporting the feed-table B and carrying bearings for the shaft C' of the main cutter-head C, extending transversely a suitable distance above the table B, as plainly indicated in Fig. 1. This main cutter-head C serves to reduce the timber throughout its width to a desired thickness, and in order to trim the side edges of the timber to a desired width I provide side cutter-heads D and D', adapted to be moved independently in a transverse direction according to the width of the timber to be dressed.

The timber is fed past the cutter-heads C, D, and D' by sets of feed-rollers E and E', of which the set of feed-rollers E is arranged in

rear of the cutter-heads, and the other set E' is arranged in the front of the cutter-head C.

When it is desired to use the machine for trimming two pieces of timber at the same time, I provide the longitudinally-extending guide-rails F and F', held transversely adjustable on the top of the feed-table B, the guide-rail F bearing in conjunction with the main cutter-head C and the side cutter-head D, while the other guide-rail F' bears in conjunction with the main cutter-head C and the other side cutter-head D'. The side cutter-heads D and D' are secured on the upper ends of spindles G and G', respectively, journaled in bearings H and H', attached to carriages I and I', respectively, mounted to slide independently one of the other on transverse guideways A', forming part of the main frame A.

Each of the carriages I and I' is provided with a bracket I², extending upward through a transverse slot in the feed-table B, and on the upper ends of the brackets I² are secured the short guide-rails F² and F³ for guiding the timber from the cutter-heads D and D'.

From the foregoing it will be seen that when the cutter-heads D and D' are adjusted transversely by moving the carriages I and I' on the transverse guideways A', then the guide-rails F² and F³ move with the cutter-heads, so as to at all times stand in the proper position relative to the cutter-heads D and D'.

Each of the spindles G G' is provided with a pulley G², connected by a belt with a pulley G³, secured on a transverse shaft G⁴, journaled in suitable bearings in the main frame A and connected by pulleys and a belt with other machinery for imparting a rotary motion to the said shaft G⁴.

The carriages I and I' are adapted to be shifted transversely and independently one of the other, and for this purpose a shifting device is provided for each of the carriages, each shifting device being under complete control of the operator, and the shifting devices being alike in construction it suffices to describe but one in detail.

A longitudinally-extending shaft J is journaled at its rear end in the corresponding carriage I or I', and its front end is journaled in the carriage K, mounted to slide trans-

versely in suitable bearings A², carried by the main frame A. The corresponding carriages K K and I I' are connected with each other by stay-rods X. On the front end of each shaft J is secured a crank-arm J' or a power-ratchet W of any approved construction, (see Figs. 5 and 6,) under the control of the operator, for turning the shaft whenever it is desired to shift the corresponding carriage I or I', as hereinafter more fully described.

On each shaft J are secured the gear-wheels J² and J³, in mesh with transverse racks J⁴ and J⁵, secured to or forming part of the main frame A, so that when the shaft J is turned the gear-wheels J² and J³ roll off on the racks and in doing so cause a transverse slide of the carriages I K or I' K. In order to securely lock each carriage I or I' in place after the desired adjustment is made, I provide a screw-rod L, extending longitudinally from one carriage K to the other carriage I or I', and the front end of each screw-rod L is provided with a square offset L' for receiving a crank-arm to turn the screw-rod, so as to screw its rear end in the carriage I or I' against the bearing A' to lock the carriages in place. An additional locking device is provided for each set of carriages I K and I' K, and this locking device consists of a shaft N, mounted to turn and to slide longitudinally in the corresponding set of carriages. On the rear end of the shaft N is secured an arm O, adapted to engage one of a series of apertures O', formed in the corresponding carriage I or I', as plainly indicated in Fig. 4, and the said shaft N is pressed by a spring N', so as to normally hold the arm O in engagement with the corresponding aperture O'. On the extreme front end of the shaft N is fulcrumed a cam-lever P, abutting against the outer face of the corresponding carriage K, the said cam-lever P serving to slide the shaft N forwardly against the tension of the spring N' to withdraw the arm O from the aperture and to allow the operator to then turn the shaft N so as to bring the arm O in alignment with another aperture O' after the corresponding carriage I or I' and its carriage K have been shifted.

Each of the outer carriages K is provided with a pointer K', indicating on a graduation K², arranged on the rear edge of the feed-table B, as plainly shown in Fig. 3, so that the operator is enabled to readily shift the carriages and the cutter-heads D and D' to a desired position, it being understood that the apertures O' for engagement by the arms O are so arranged relative to the graduations K² that when the pointer K' stands on a graduation mark the arm O is adapted to engage the aperture O'.

It is understood that the machine can be used as a planer for trimming single pieces of timber, and in this case the guide-rails F and F' are removed, and the machine is ca-

pable of trimming timber of considerable width.

When the rails F and F' are in position, then two pieces of timber can be fed simultaneously through the machine at one time, and also while the machine is running the operator is enabled to shift any one of the cutter-heads D or D' transversely for trimming timber of a different width without disturbing the other cutter-head or stopping the machine.

Having thus described my invention, I claim as new and desire to secure by Letters Patent—

1. A planer provided with a side cutter-head, a carriage mounted to slide transversely and carrying the bearings for the shaft of the said cutter-head, a second carriage mounted to slide transversely and connected with the first-named carriage, a shaft journaled in the said carriages, gear-wheels on the said shaft, and fixed racks in mesh with the said gear-wheels, as set forth.

2. A planer provided with a side cutter-head, a carriage mounted to slide transversely and carrying the bearings for the shaft of the said cutter-head, a second carriage mounted to slide transversely, a shaft journaled in the said carriages, gear-wheels on the said shaft, fixed racks in mesh with the said gear-wheels, a locking device for the said carriages comprising a shaft mounted to turn and to slide longitudinally in the said carriages, an arm on the said shaft for entering one of a series of apertures in one of the carriages, and a cam-lever for imparting a sliding and turning movement to the said shaft, as set forth.

3. A planer provided with a side cutter-head, a carriage mounted to slide transversely and carrying the bearings for the shaft of the said cutter-head, a second carriage mounted to slide transversely, a shaft journaled in the said carriages, gear-wheels on the said shaft, fixed racks in mesh with the said gear-wheels, a locking device for the said carriages comprising a shaft mounted to turn and to slide longitudinally in the said carriages, an arm on the said shaft for entering one of a series of apertures in one of the carriages, a cam-lever for imparting a sliding and turning movement to the said shaft, and a spring pressing the said sliding and turning shaft, as set forth.

4. A planer provided with a side cutter-head, a carriage mounted to slide transversely and carrying the bearings for the shaft of the said cutter-head, a second carriage mounted to slide transversely, a shaft journaled in the said carriages, gear-wheels on the said shaft, fixed racks in mesh with the said gear-wheels, a locking device for the said carriages comprising a shaft mounted to turn and to slide longitudinally in the said carriages, an arm on the said shaft for entering one of a series of apertures in one of the carriages, a cam-lever for imparting a sliding and turning

movement to the said shaft, and a pointer on one of the carriages, adapted to indicate on a fixed graduation, as set forth.

5. In a planer, the combination with a supporting-frame, carriages mounted to slide transversely of the frame and connected with each other, a cutter-head mounted in one carriage and means for operating the said carriages in unison, of a shaft mounted to turn 10 and slide in the carriages and provided at

one end with an arm adapted to engage an aperture in one of the carriages, and means for operating the said shaft, as set forth.

In testimony whereof I have signed my name to this specification in the presence of 15 two subscribing witnesses.

EDWARD RAWSON.
